UNITED STATES PATENT OFFICE.

WILLIAM THOMAS BUCKINGHAM ROBERTS, OF LEICESTER, ENGLAND, ASSIGNOR TO UNITED SHOE MACHINERY CORPORATION, OF PATERSON, NEW JERSEY, A CORPORATION OF NEW JERSEY.

FASTENING-INSERTING MACHINE.

Application filed April 14, 1925, Serial No. 23,132, and in Great Britain May 2, 1924.

This invention relates to fastening-inserting machines and is illustrated herein as embodied in a machine for inserting loose nails.

5 In a fastening-inserting machine which is provided with an awl operative to pierce the work preparatory to the driving of the fastening, the awl provides a convenient and satisfactory means by which to feed the work through the machine. Not all fastening-inserting machines, however, are provided with awls. Thus in the case of machines particularly intended for shoe repairing, it is desirable to make the machines 10 as simple and inexpensive as possible, and the somewhat greater complexity and costliness of awl-type machines has been considered sufficiently undesirable to make it worth while to build simpler machines without awls for repair work. An example of 15 such a machine is that disclosed in United States Letters Patent No. 1,688,436, granted October 23, 1928, on an application filed in the name of William T. B. Roberts. In the 20 machine disclosed therein there is provided a feed member engaging frictionally the edge of the work and oscillated to advance the work through the machine.

It is an object of the present invention 25 to provide a work-feeding device applicable though not necessarily limited to awl-less fastening-inserting machines which will feed the work as positively and certainly as does an awl feed.

30 In the illustrated embodiment of the invention, in accordance with one of its features, this object is attained by the provision of novel work-feeding mechanism, including a work-feeding member arranged to engage partially inserted nails successively, thus positively feeding the work through the machine. This is facilitated, in accordance with another feature of the invention, by the provision of novel fastening-inserting 35 instrumentalities arranged to impart a plurality of blows in succession to each fastening driven, the fastening being partially inserted by the first blow and the work being fed before the insertion of the fastening is 40 completed by the second blow. As herein illustrated, the successive blows are struck by two separate drivers, and the work is fed by a flat feed-finger or plate moved back and forth in each cycle of operation of the ma-

chine in a plane substantially parallel to 55 that of the surface of the work operated upon to feed the work from the position at which the first blow is struck to that in which the second blow is struck.

For purposes of shoe-repair work it is 60 often desired to insert a row of fastenings across the work. Thus in attaching a half-sole to a shoe, it is usual to nail the rear end of the half-sole to the shoe by a row of nails 65 arranged transversely of the sole of the shoe. Since the feed mechanism of the present invention, while in no sense limited in its utility to machines used for shoe-repair work, was developed with such work 70 particularly in mind, in accordance with a further object of the invention the work-feeding mechanism disclosed herein is of such a nature that it is adapted to feed the work in a direction transversely of the edge 75 of the work as well as in a direction parallel to the edge.

Thus another feature of the invention 80 comprises the provision in a fastening-inserting machine of feed mechanism adapted to feed a shoe to and past the fastening-inserting instrumentalities of the machine in either of two mutually transverse paths, that is two paths each transverse with respect to the other. With this in view, a 85 work-feeding member such as a nail-engaging finger is provided with two nail-engaging surfaces arranged at right angles to each other, and means is provided for moving the feeding member alternatively in either one of two directions, each of said directions 90 being substantially at right angles to one of said nail-engaging surfaces. With this construction in view, a further feature of the invention comprises an arrangement whereby the driver which strikes the second blow 95 upon each nail is formed and arranged to hit and drive the nail whether fed in one or the other of those directions.

Fastening-inserting machines of the type 100 referred to are usually provided with a work support in the form of a horn having a clenching surface or cavity of a form to facilitate the clenching of the fastenings. In order that the clenching may be performed properly, this clenching surface 105 should be positioned in line with the point of the nail when the second driving blow is struck and the position of the nail for this

blow is variable. Therefore, in accordance with a further feature, the invention provides a clenching member such as a horn which is movable to bring its clenching surface alternatively into the line of drive at the several positions at which the fastening insertion may be completed by the second blow and means is provided for latching the horn in either of those positions.

With the above and other objects and features in view the invention will now be described as illustrated in the accompanying drawings and pointed out in the accompanying claims.

In the accompanying drawings,

Fig. 1 is a side elevation, partly in section, of the head and part of the driving mechanism of a nail-inserting machine of the type disclosed in said application Serial No. 600,497, with the present invention embodied therein;

Fig. 2 is a horizontal section of the machine showing the work feed mechanism and work support adjusting mechanism in plan view;

Fig. 3 is a front elevation of the nozzle and fastening-inserting drivers of the machine;

Fig. 4 is a transverse section through the nozzle of the machine on the line 4—4 of Fig. 1; and

Fig. 5 is a vertical section on the line 5—5 of Fig. 4.

The general organization of the illustrated machine is in accordance with that of Figs. 1, 2 and 8 of said Letters Patent No. 1,688,436, to which reference may be had for a full description thereof. The machine is provided with a work support or horn 20 mounted for rotary movement about a short shaft 12 which may be latched in either one of two positions relatively to the operating instrumentalities of the machine by mechanism more fully described hereinafter. The machine is also provided with a head 26 vertically movable to permit the work to be placed upon and removed from the work support 20 when the machine is at rest and moved vertically to a much less extent during each cycle of operation of the machine to relieve the pressure upon the work as the work is fed. Head 26 is guided in its vertical movement by a vertical rod 30 which extends through a bearing 32 in the head of the machine and which carries at its upper end a driver carrier 40. A second vertical rod 34 to the rear of rod 30 is fixed at its upper end to bracket 36 forming part of head 26 and passes down through a lug 38 carried by the head of the machine toward the base of the machine, serving also to guide head 26 in its vertical movement. A spring 46, surrounding rod 34 and bearing against the lower face of a

lug 44 at the rear of driver carrier 40 and against lug 38, urges driver carrier 40 upwardly until the upper face of lug 44 encounters the lower face of a projecting portion 48 of bracket 36. In this connection it may be noted that rod 30 is reciprocated from a cam 266, as more fully described in said Letters Patent No. 1,688,436, rod 30, in co-operation with spring 46, serving to give to driver carrier 40 its driver reciprocating movement and to give to the head of the machine its vertical work-relieving movement during the feeding of the work and its greater movement which permits the work to be removed from or replaced on horn 20, as well as serving to rock a lever 120 through its connection by a link 114 to driver carrier 40. Lever 120 controls the passage of the fastenings from hopper 56 to the nail tube 100 which leads to the cylindrical driver passage or throat opening 142 of nozzle 28.

Turning now to the novel mechanism of the present invention, the head 26 of the machine has attached thereto a bracket 202 extending along its right-hand side and having formed in it a guideway 203 extending from front to rear of the machine. In this guideway is mounted a slide 204 having a curved, forwardly projecting portion 205 formed with an arcuate slot 206 the center of curvature of which, indicated in Fig. 2 at 207, lies in a vertical plane passing through the axis of driver 208 and extending rearwardly. Located in slot 206 is a pair of vertical studs 209, each carrying a roll 210 guided for arcuate movement by the slot. Studs 209 are secured to a pair of upper and lower plates 211, 212 sliding on the forwardly extending portion 205 of slide 204, and, accordingly, supported for arcuate movement about center 207. The lower plate 212 is extended forwardly and has pivotally connected to it by a horizontal pivot 213 a feed member comprising a plate or finger 214 pressed downwardly toward the work by a flat spring 215. At its forward end feed finger 214 is formed with a pair of vertical faces 216, 217. Face 216, which extends forwardly and rearwardly of the machine, is, before the starting of the feeding movement, at the right of the path of the driver 208 carried by driver carrier 40 and face 217 extends transversely of the machine at the rear of this path. During the operation of the machine, finger 214 is given an oscillating movement either to the right and left or forwardly and rearwardly according to the desired direction of feed of the work, and as finger 214 is thus moved, one or the other of faces 216, 217 engages a partly driven fastening positively to feed the work piece.

In order to accomplish this result, a latch lever 218 (Fig. 2) is provided pivoted at 219

to slide 204 and arranged alternatively to lock slide 204 against movement while permitting arcuate movement of plates 211 and 212 about center 207, or to release slide 204 for forward and rearward movement while locking plates 211 and 212 to slide 204. This lever 218 is provided with a notch 221 arranged, when the lever 218 is swung in a clockwise direction, as viewed in Fig. 2, for engagement with a block 222 carried by plate 211. At its rearward extremity lever 218 is provided with a second notch arranged to engage a block 220 carried by bracket 202 as shown in Fig. 2. Pivoted at 223 to a pair 15 of ears formed on plates 211, 212 is a link 224 pivoted also to an arm 225 slidably mounted upon a vertical rod 226. A lug 227 formed on bracket 202 supports arm 225. Fixed to rod 226 somewhat below arm 225 is 20 an arm 228 having secured to its extremity a pin 229 passing upwardly through an opening in arm 225 so that arm 225 will be rocked by rod 226 but will not be affected by vertical movement of rod 226. Rod 226 carries also 25 an arm 230 provided with a cam roll 231 urged toward engagement with a surface cam track formed upon a cam member 288 by a spring 290. To vary the extent of the rocking movement of rod 226 and, accordingly, 30 to vary the extent of feed, an adjusting screw 232 is provided carried by a stationary part of the machine frame and arranged to engage a lug carried by arm 230 to limit the movement of cam roll 231 in the direction of 35 cam 288.

The mechanism which has just been described is operative to reciprocate plates 211 and 212 and the feed finger 214 carried thereby either in a forwardly and rearwardly direction if slide 204 is free to move forwardly and rearwardly and is latched by latch lever 218 to plates 211 and 212 or transversely if slide 204 is locked against movement by latch lever 218 but is released from plates 211 and 212. Under the circumstances last mentioned, plates 211 and 212 are given an arcuate movement about center 207 and, accordingly, face 216 of feed member 214 is moved transversely of the machine in a path which, on account 55 of its comparatively large radius and short arc, sufficiently approximates a straight line.

In the illustrated machine the proportions of the parts are such that if no change is made in the arc of rocking movement of rod 226, the extent of the transverse feeding movement given to finger 214 will be somewhat greater than that of the forward movement since it is ordinarily desired to space nails inserted across the rear end of a half-sole somewhat closer than those inserted around the periphery of the sole of a shoe.

An edge gage 234 is illustrated in Fig. 1 arranged to guide the work fed transversely of the machine. Edge gage 234 is positioned 60 beneath feed finger 214 and is formed at the

forward end of a rearwardly extending bar 235 pivoted at its rear end by a vertical pivot 236 carried by a block 237 attached by a screw-and-slot connection 238 to bracket 202. A spring plunger 240 carried by bracket 202 70 is arranged to enter a shallow opening formed in bar 235 so as to latch the latter in position to hold gage member 234 in operative position while at the same time permitting the gage member to be swung rearwardly out of the way when it is desired to insert fastenings transversely of the work or when, for any other reason, the gage member either is unnecessary or in the way. 75

During the operation of the machine, nozzle 28 is moved downwardly into engagement with the upper face of feed finger 214 to clamp the work against work support 20. Driver 208 then drives a fastening into the work, leaving the fastening projecting a distance substantially equal to the thickness of feed finger 214. The work piece is then positively fed by the engagement of finger 214 with the partly driven fastening either transversely or forwardly of the machine according to the position of latch lever 218. In order to complete the driving of the fastenings, the throat member or nozzle 28 is provided with a pair of vertical faces 243, 244 (Fig. 4) formed at right angles to each 80 other and extending toward the left and toward the front of the machine respectively. These faces have formed in them vertical grooves 245, 246, which receive tongues 247, 248 formed upon a driver block 249 of a 85 shape conforming to that of nozzle 28 and thus guided for vertical, sliding movement. Fixed to driver block 249 is a bar 250, the upper end of which is hook-shaped, as shown 90 in Fig. 3, to engage a co-operating hook member 251 carried by the forward end of arm 120. Resting on the upper face of driver block 249 is the lower end of a rod 253 guided for vertical movement in an opening 95 formed in the throat member 28 and carried 100 by and vertically reciprocated with the driver carrier 40 which carries also driver 208. Thus at the same time that driver 208 drives a fastening part way into the work, driver block 249 completes the driving of the individual fastening, the insertion of which 105 was started in the preceding cycle. The area and shape of the lower end of driver block 249 are such as to do this whether the work is fed transversely or forwardly and 110 whatever the length of the feeding movement within the limits permitted by the machine. In this connection it may be noted that driver block 249 extends generally forwardly and to the left of the path of driver 115 208 while feed finger 214 extends rearwardly and to the right so that the two do not interfere with each other. Moreover, driver block 249 is moved upwardly in the operation of the machine before finger 214 makes 120

125 130

its feeding movement and is not moved downwardly until after finger 214 has been retracted.

Since the final driving, and, therefore, the 5 clenching of the fastenings, is effected either to the left or in front of the driver bar, it is desirable to alter the position of the horn tip on which is formed a clenching surface, illustrated as a clenching cavity 258. Accordingly, horn shaft 12 is carried by a block 255 pivotally secured at 256 to a bracket 257 secured to the frame of the machine. Thus clenching cavity 258 may be swung laterally from a position at the left of the 15 path of driver 208 to a position in front of the path of that driver. To lock the horn shaft in either one of these two operative positions, block 255 is provided with a spring plunger 260 carried by a handle 259, 20 plunger 260 being arranged to engage either one of two V-shaped recesses 261, 262 formed in bracket 257. Between the recesses 261, 262 is a hardened block 263 the faces of which form one side of each recess and over 25 which the plunger snaps when the horn block 255 is adjusted. At its end remote from bracket 257 plunger 260 is provided with a ring 264 by which it may be withdrawn so as to allow the horn to be swung 30 about pivot 256 into an inoperative position remote from nozzle 28.

It should be understood that the word "nail" is used herein as of a scope to include not only headed nails, but also other driven 35 fastenings, such as pegs, slugs, and staples.

Having described the invention, what I claim as new and desire to secure by Letters Patent of the United States is:

1. A fastening-inserting machine having, 40 in combination, a work support and fastening-inserting means arranged to strike hammer blows on each of a plurality of fastenings inserted successively in a work piece carried by the support and to strike a second hammer blow on each fastening during 45 the cycle of operation of the machine succeeding that in which the first blow is struck on that fastening.

2. A fastening-inserting machine having 50 a plurality of drivers and operating means arranged to cause the several drivers to operate successively and individually on each of the fastenings inserted.

3. A fastening-inserting machine having 55 a plurality of drivers arranged to operate successively on each of the fastenings inserted, and means for feeding the work arranged to present the fastenings partly driven by one driver one at a time to another driver to be completely driven thereby.

4. A fastening-inserting machine having 60 fastening-inserting means arranged to strike two hammer blows in succession on each of the fastenings to be inserted, each blow being 65 in a direction to drive the fastening into

a work piece, and means for feeding the work between the striking of the two blows.

5. A fastening-inserting machine having fastening-inserting means arranged to strike a plurality of blows in succession upon each of the fastenings to be inserted, and means 70 arranged to engage and to move a partially inserted fastening between the striking of two blows to feed the work.

6. A fastening-inserting machine having 75 a pair of drivers arranged to operate successively on each of the fastenings inserted, and means arranged to engage and to move a fastening partially inserted by one driver to feed the work and to bring the partly 80 driven fastening into position to be completely driven by the other driver.

7. A fastening-inserting machine having 85 means to drive fastenings part way into the work, a finger arranged to engage a partly driven fastening from one side, means for moving the finger back and forth in a path substantially at right angles to the length of the fastening to cause the finger to feed the work by engagement with successive partly driven fastenings, and means to complete 90 the driving of the fastenings.

8. A fastening-inserting machine having 95 a horn arranged to support a shoe sole upwardly, means for inserting fastenings into the sole of the shoe, and mechanism arranged to feed the shoe alternatively in any of a plurality of mutually transverse paths.

9. A nail-inserting machine having nail-driving instrumentalities, a work-feeding member, and means for moving said member alternatively in either of two different paths to feed the work correspondingly to and past the nail-driving instrumentalities. 100

10. A nail-inserting machine having nail-driving instrumentalities, a work-feeding member, and means for reciprocating said member alternatively in either of two angularly related paths to feed the work correspondingly to and past the nail-driving 105 instrumentalities.

11. A fastening-inserting machine having a work-feeding member arranged to engage a fastening partly inserted in the work, and means for moving said feeding member alternatively in either one of two mutually transverse paths, thereby feeding the work in either one of two directions. 115

12. A fastening-inserting machine having fastening-inserting instrumentalities, a work-feeding finger arranged to engage a partly driven fastening to feed the work through the machine, and means for moving the finger alternatively either transversely or forwardly of the machine to feed the 120 work in the corresponding direction.

13. A fastening-inserting machine having a work-feeding finger provided with two relatively transverse surfaces arranged to engage a fastening partly inserted in the 125

work, and means for moving said finger alternatively in either one of two mutually transverse paths, thereby feeding the work in either one of two directions.

5 14. A fastening-inserting machine having a slide, means for reciprocating said slide, a work-feeding member carried by said slide and mounted for movement transversely of the slide, and means for alternatively locking the slide against movement while permitting movement of the feeding member relatively to the slide or locking the feeding member to the slide but permitting movement of the slide.

10 15. A fastening-inserting machine having a slide, a work-feeding member carried by said slide and mounted for movement transversely thereof, a latch carried by the slide and operable to lock the feeding member to the slide or alternatively to release the feeding member for movement relatively to the slide and to lock the slide against movement, and means connected to the feeding member and movable to give the feeding member movement transversely of or in the direction of the slide according as the feeding member is moved relatively to the slide or is locked to the slide.

15 16. A machine for operating upon shoe parts having a slide, means for reciprocating said slide, a work-feeding member mounted for arcuate movement relatively to said slide, and means for alternatively locking the slide against movement while permitting movement of the feeding member relatively to the slide or locking the feeding member to the slide while permitting movement of the slide.

20 17. A machine for operating upon shoe parts having a slide provided with an arcuate slot, a work-feeding member having a bearing in said slot whereby the feeding member may have arcuate movement relatively to the slide, and a latch carried by the slide and operable to lock the feeding member to the slide.

25 18. A machine for operating upon shoe parts having a slide provided with an arcuate slot, a work-feeding member having a bearing in said slot whereby the feeding member may have arcuate movement relatively to the slide, and a latch carried by the slide and operable to lock the feeding member to the slide or alternatively to release the feeding member for movement relatively to the slide and to lock the slide against movement.

30 19. A fastening-inserting machine having a driver, a slide provided with an arcuate slot, a work-feeding member arranged to feed the work to and past the driver, said feeding member having a bearing in said slot whereby the feeding member may have arcuate movement relatively to the slide, a latch carried by the slide and operable to

lock the feeding member to the slide or alternatively to release the feeding member for movement relatively to the slide and to lock the slide against movement, and means connected to the feeding member and movable to give the feeding member an arcuate or a rectilinear movement according as the feeding member is movable relatively to the slide or is locked to the slide.

35 20. A fastening-inserting machine having a work-supporting horn provided with a clenching surface, and means for positioning the horn for rotation about either one of two fixed axes with its clenching surface in position to clench nails at either one of two corresponding nail-clenching positions.

21. A fastening-inserting machine having means for feeding the work in either one of two mutually transverse paths, a horn having a clenching cavity, and means for positioning the horn with said clenching cavity in either one of two predetermined positions according as the work is fed through one or the other of said paths.

22. A fastening-inserting machine having means for feeding the work in any one of a plurality of mutually transverse paths, a horn having a clenching surface, and means for positioning the horn in any one of a plurality of predetermined positions corresponding to the clenching position according as the work is fed through one or another of said paths.

25 23. A fastening-inserting machine having a work-supporting horn provided with a clenching cavity, horn-supporting means arranged to be locked in either one of two predetermined positions to position the horn in the machine with the clenching cavity in position to clench nails at either one of two nail-clenching positions, and a driver operative to drive nails through the work to clinch their points against the surface of the clenching cavity in either position of the horn.

28 24. A fastening-inserting machine having fastening-inserting mechanism arranged to impart two hammer blows in succession to each of the fastenings inserted, means for feeding the work between the striking of the two blows in either one of two mutually transverse paths, a work-supporting horn having a clenching cavity, and horn-supporting means arranged to position the horn with its clenching cavity in either one of two clenching positions according as the work is fed in one or the other of said paths.

32 25. A fastening-inserting machine having a throat member, a driver arranged to reciprocate through the opening of the throat member, and a second driver arranged to reciprocate through a path parallel to the first and guided in its reciprocation by surfaces formed upon the exterior of the throat member.

35 26. A throat member for fastening-insert-

ing machines having a driver passage and a pair of driver-guiding slots independent of the driver passage, all running in the same general direction with the surfaces of one slot at an angle to corresponding surfaces of the other slot.

27. A fastening-inserting machine having a nozzle with a throat opening therethrough of substantially the cross-section of the fast-

ening to be inserted, a driver reciprocable through said throat opening, and a second driver reciprocable in parallel relation to the first and guided in its reciprocation by slots formed on the exterior surface of the throat member.

In testimony whereof I have signed my name to this specification.

WILLIAM THOMAS BUCKINGHAM ROBERTS.
